UNITED STATES PATENT OFFICE.

ELMER F. ASHBROOK, OF JAMESPORT, MISSOURI.

DESIGN FOR A JEWELER'S CABINET.

46,307.

Specification for Design.

Patented Aug. 25, 1914.

Application filed June 25, 1914. Serial No. 847,318. Term of patent 14 years.

To all whom it may concern:

Be it known that I, ELMER F. ASHBROOK, a citizen of the United States, residing at Jamesport, in the county of Daviess and State of Missouri, have invented a new, original, and ornamental Design for Jewelers' Cabinets, of which the following is a specification, reference being had to the accompanying drawing, forming part thereof.

The figure is a perspective view of a jeweler's cabinet, showing my new design.

I claim:

The ornamental design for a jeweler's cabinet as shown.

ELMER F. ASHBROOK.

Witnesses:

J. S. ABERCROMBIE,
S. B. CROPPER.
